CLAIM

The ornamental design for a handle for a medical device, as shown and described.

DESCRIPTION

FIG. 1 is a rear perspective view of a handle for a medical device of the present invention;

FIG. 2 is a front perspective view of the handle for a medical device of FIG. 1;

FIG. 3 is a right side view of the handle for a medical device of FIG. 1;

FIG. 4 is a left side view of the handle for a medical device of FIG. 1;

FIG. 5 is a front view of the handle for a medical device of FIG. 1;

FIG. 6 is a rear view of the handle for a medical device of FIG. 1;

FIG. 7 is a top view of the handle for a medical device of FIG. 1; and,

FIG. 8 is a bottom view of the handle for a medical device of FIG. 1.

The broken lines immediately adjacent the shaded areas represent the bounds of the claim, and all other broken lines are included for the purpose of illustrating the unclaimed portions of the handle for a medical device. None of the broken lines form a part of the claimed design.
